UNITED STATES PATENT OFFICE.

HEINZ BRANDENBERG, OF SCHWIENTOCHLOWITZ, GERMANY.

THEODOLITE.

1,128,578.

Specification of Letters Patent. Patented Feb. 16, 1915.

Application filed February 15, 1912. Serial No. 677,712.

To all whom it may concern:

Be it known that I, HEINZ BRANDENBERG, a citizen of the German Empire, and residing at Schwientochlowitz, Upper Silesia, German Empire, have invented certain new and useful Improvements in Theodolites, of which the following is a description.

The present invention relates to theodolites for measuring horizontal and vertical 10 angles.

The instrument differs from the known ones mainly in the arrangement of alidade and the graduated arc, which are located around a common central axis, mounted to swing 15 around a supporting spike or peg. By this means the centering and horizontal adjustment of the instrument are rendered reliable and invariable. Both the axis of the alidade, as also that of the graduated arc are in the 20 form of sleeves adapted to rotate around each other and also around a common axis. By this means very reliable operation of the apparatus is attained and it is rendered especially adaptable for mine surveying 25 purposes.

In the accompanying drawing an embodiment of the invention is illustrated, Figure 1 being a side elevation partly in section, Fig. 2 a similar view seen at right angles to 30 the view in Fig. 1, Fig. 3 a plan of the device with the steel peg or spike in plan view and the sleeve fitting the same in section, Fig. 4 shows the graduation of the main 35 arc, Fig. 5 that of the vertical arc, Figs. 6 and 7 show the signals in sectional side elevation and plan, Fig. 8 is a sectional view of a part of the spike and sleeve and Fig. 8^a is a cross section through the same parts, and 40 Figs. 9 and 10 show a modified form of the central axis in vertical section and plan respectively.

The instrument is suspended on the peg or spike 1 by means of its conical sleeve 2, the jaws 3 of which may be pressed together 45 by means of the butterfly nut and screw 4, 5. A second screw 6 serves to clamp the sleeve to the spike. Any unintentional loosening of the sleeve is prevented by means of a bolt 8 mounted on a spring 7 and engaging 50 an annular groove of the spike. In order to disengage the sleeve from the spike, the clamping screw 6 must first be loosened and the bolt 8 then withdrawn from the groove by means of its button. A bending around or 55 breaking of the spring 7 is prevented by the lug 9 (Fig. 6).

The jaws 3 support the ball end (Fig. 2) of the axis 10 of the pendulum theodolite, on the lower, slightly enlarged end of which, the sleeves 11 and 12 are mounted to turn, 60 being retained in position by means of the annular disk 13 secured by the screw 14. At the upper end a ring 15 screwed or otherwise secured to the sleeve 11 holds the two sleeves 11 and 12 in proper relative position. The lower part of the sleeve 11 is connected to a disk having the graduations 65 16 around its edge, around which the verniers 17 of the disk of the sleeve 12 are located.

The fine adjustment for the graduated arc 16 is arranged in the usual manner at 18 and that of the alidade arc 17 at 19. The latter is mounted on a screw spindle 20 supported on a collar 20', which simultaneously prevents the upward movement of the sleeve 11, 70 on the spindle 10.

A frame 21 is suspended from the lower end of the sleeve 11, in which frame the telescope 22 is mounted, the position of the axis 80 of the said telescope being adjustable by means of the screw 24. The telescope is provided as usual with the vertical arc 25 and the fine adjustment 26.

The instrument is adjusted in the horizontal plane by means of the box air levels 85 27 and 28. The latter is mounted on a special plate 29, screwed to the frame 21, so that the air levels may be removed with the plate, without loosing their adjustment. 90

In Fig. 4 the scale of the main arc is illustrated, which is reversed as regards that of the ordinary theodolite, and Fig. 5 shows the scale of the circle of altitude.

The distance of the ball 34 to be sighted 95 with the swinging theodolite, from the center line of the attachment sleeve, must be exactly equal to the distance of the center line of the telescope from the center of the ball of the axis 10 of the instrument, in 100 order to insure the line of sight being parallel to the connecting line of the point of suspension of the instrument. In order to avoid inaccuracies in the polygonal angles, the distance $a-b$ (Fig. 1) must be the same 105 both with the pendulum theodolite and with the signals.

The instrument might also be employed in an upright position, or on a stand. With this object in view the top of the stand 110 illustrated in Fig. 8 is provided with an upwardly extending pin 35, which corresponds

in shape with the front end of the spike or peg 1.

In mines, the spike is driven into the wood work, between the bricks of brick-work or 5 into the coal or partition rock and in order to prevent deformation of the head of the spike it is advantageously provided with a cross boring for the reception of a striking iron or bolt.

10 The novelty of the present instrument consists in the arrangement of the main and vernier arcs or circles of the theodolite on a special spindle 10 and in the arrangement of the spindle 20 on this spindle.

15 In the modification illustrated in Figs. 9 and 10, the horizontal adjustment of the theodolite is facilitated. In this case, the jaws 36 engage the upper ball 37 of a tube 38 which is widened out toward its lower 20 end, and is provided with four arms 39 arranged in the form of a cross, the outer ends of said arms being enlarged and turned down, hook-like and provided with holes. The boring in the ball 37 is cylindrical in 25 its upper part, hemispherical toward its lower part, and flared at the bottom. A spindle 40 has its ball 41 mounted in the part 37, and the lower end of this spindle engages in a second spindle 42 having at 30 its upper end four horizontally extending arms 43, in the form of a cross, the said arms having screw-threaded ends extending through the borings of the arms 39. By means of nuts 44 having milled edges and 35 clamping plates 45 the spindles 40 and 42 may be adjusted in any desired manner around the ball 41. A closing screw 46 is screwed into the top of the hollow ball 37 to prevent any upward movement of the ball 40 41 within the same.

The exterior surfaces of the arms 39, are cylindrically turned to fit the interior of the clamping plates 45. The lower end of the spindle 42 carries the sleeves 11 and 12 and

the apparatus is otherwise the same as that 45 illustrated in Figs. 1 and 2.

In utilizing the horizontal adjusting device illustrated in Figs. 9 and 10, the apparatus is first adjusted by hand, so that the air levels register approximately and the clamping screw 4 is then tightened up. The exact adjustment of the air levels is then effected by means of the screws 44.

The present pendulum theodolite is intended as a substitute for the compass and those compass-instruments which are constructed for taking measurements in the presence of iron, and it is also to be employed for mining purposes for effecting 60 polygonal measurements.

I claim as my invention:—

1. In a suspended theodolite comprising a central axis 10 having two sleeves 11 and 12 around the same, the combination of a ball formed at the upper end of the said 65 axis 10, a sleeve 2 having jaws 3 to embrace the said ball, a graduated arc 16 integral with the said sleeve 11, an alidade arc 17 above the graduated arc and combined with the said sleeve 12 and a fine adjustment screw spindle 20 attached directly to the central axis.

2. In a suspended theodolite comprising a central axis, the combination of a ball formed at the upper end of said axis, a hollow supporting arm having a hollow sleeve and ball shell to engage said ball, means for adjusting the said ball and hollow sleeve as regards each other, clamping jaws to engage the outer hollow sleeve, and adjusting 75 screws engaging the free end of the ball spindle.

In testimony whereof I affix my signature in the presence of two witnesses.

HEINZ BRANDENBERG.
